(57) **CLAIM**

The ornamental design for an antenna housing, as shown and described.

DESCRIPTION

FIG. 1 is a front perspective view of an antenna housing, showing our new design;

FIG. 2 is a rear perspective view of the antenna housing shown in FIG. 1;

FIG. 3 is a left side view of the antenna housing shown in FIG. 1;

FIG. 4 is a right side view of the antenna housing shown in FIG. 1;

FIG. 5 is a front view of the antenna housing shown in FIG. 1;

FIG. 6 is a rear view of the antenna housing shown in FIG. 1; and,

FIG. 7 is a top view of the antenna housing shown in FIG. 1.
